UNITED STATES PATENT OFFICE.

ERNEST E. ELLMANN, OF ST. LOUIS, MISSOURI, ASSIGNOR OF ONE-HALF TO ISAAC HAAS, OF ST. LOUIS, MISSOURI.

SHOE-STRETCHER.

1,117,818.

Specification of Letters Patent. Patented Nov. 17, 1914.

Application filed October 17, 1913. Serial No. 795,626.

To all whom it may concern:

Be it known that I, ERNEST E. ELLMANN, a citizen of the United States, residing at the city of St. Louis, State of Missouri, have 5 invented certain new and useful Improvements in Shoe-Stretchers, of which the following is a specification.

This invention relates to devices for stretching boots and shoes and the like, and 19 has for its object to provide a new and improved device of this character which is simple and strong in construction, effective in operation and comparatively inexpensive to manufacture.

15 Heretofore, shoe-stretchers have been made in the form of a last that is divided longitudinally into two halves, which are hinged together at the heel and have registering grooves in the inner faces for the reception 20 of a spreading block having somewhat the form of an arrow-head, this block being moved longitudinally in the grooves by means of a screw-threaded rod which passes through a screw-threaded opening in a stationary block-held in recesses in the inner 25 faces of the halves of the last. In practice, this shoe-stretcher has been found to be objectionable and ineffective, because the halves would spread apart greater at the extreme forward end or toe of the last than 30 elsewhere, thus causing the toe of the shoe to be stretched greater than the vamp, and, sometimes, when the halves were being spread apart at the toe, the spreading block 35 would travel out of the grooves in the halves and then drop out of its position so that it would not reenter the grooves without having to remove the last with the halves spread apart from the shoe.

40 This improved shoe-stretcher obviates these objectionable features.

Further, the present invention consists of the novel features of construction and arrangement of parts hereinafter more fully 45 described and pointed out in the claims.

In the accompanying drawings forming part of this specification, in which like numbers of reference denote like parts wherever they occur, Figure 1 is a perspective view of 50 a shoe-stretcher embodying the present invention; Fig. 2 is a top plan view, partly in section, of the shoe-stretcher, showing the stretching parts spread apart; Fig. 3 is a longitudinal sectional view on the line 3—3, 55 Fig. 2; Fig. 4 is a transverse sectional view

on the line 4—4, Fig. 2; and Fig. 5 is a perspective view of a corn or bunion attachment for the stretcher.

The shoe-stretcher embodying the present invention consists of a last 1 having the upper part of its forward portion cut away 60 to form a recess 2 and a forwardly-extending sole portion 3. Said last consists of two complementary halves 4, the inner faces of which extend longitudinally in the middle 65 of the last and are joined together securely by sealing or in any other suitable manner. Each half 4 has a groove 5 in its inner face, which grooves slope downwardly from the upper part of the heel of the last to the rear 70 wall of the recess 2 and register with each other to form an opening for the reception of a screw-threaded rod 6, there being, also, an angular depression 7 in the inner face of each half 4 for the reception and retention 75 of a nut 8 through which said rod, also, extends, so that, whenever the rod 6 is rotated, the nut 8 will remain stationary with respect thereto and will cause said rod to travel either forwardly or rearwardly for the purpose 80 hereinafter described. The rear end of the rod 6 extends beyond the heel of the last 1 and bears a handle 9 by means of which said rod is operated. The forward end of the rod 6 projects beyond the rear 85 wall of the recess 2 and extends between the inner faces of a pair of complementary separable members 10, which members rest upon the sole portion 3 of the last, there being opposed grooves 11 in the inner faces of the 90 members 10 for the reception of the forward portion of the rod 6, when said members are drawn together in the manner hereinafter described. In order to permit the members 10 to be spread apart readily and, also, to 95 prevent the rear wall of the recess 2 from obstructing the movement of the members 10, the portions 12 of the halves 4 that form the rear wall of the recess 2 diverge rearwardly, and the rear ends 13 of the members 10, in like manner, diverge rearwardly so that same will fit closely against the diverging portions 12, when said members are drawn together.

The reduced forward end 14 of the rod 6 105 is revolvably retained in a central opening in a member 15 by means of a washer 16 or the like, which is secured to the reduced end 14 by a pin 17 or other suitable means, there being a depression 18 in the inner 110

face of each member, which depressions register with each other and receive the member 15 when the members 10 are drawn together. Said member 15 is preferably formed with a U-shaped cross-sectional configuration and is arranged so that its flanges 19 extend forwardly to receive therebetween the inner ends of a pair of toggle links 20 which inner ends of said links are pivoted to said flanges adjacent to the sides thereof by means of pins 21 or the like. The outer ends of the toggle links 20 extend between the flanges 22 of a pair of channel-irons 23 and are pivotally attached to said flanges by means of pins 24 or the like, said channel-irons being secured in the depressions 18, respectively, by screws 25 or other suitable means and being preferably arranged in spaced parallel relation so that their flanges 22 extend inwardly toward the member 15. A pair of links 26 having their forward ends pivotally connected to the member 10, respectively, by means of screws 27 or the like, extend rearwardly in slots 28 in the halves 4 of the last 1, being pivotally connected at their rear ends to said halves by screws 29 or the like. By this arrangement, whenever the rod 6 is rotated in the direction to travel forwardly, the member 15 will, also, travel in the same direction and thereby cause the member 15 to move the inner ends of the links 20 forwardly, whereby the toggle links 20 exert outward pressure upon the channel-irons 23, with the result of causing the members 10 to spread apart in parallel or nearly parallel relation, the links 26 preventing forward movement of the members 10 while the latter are moved apart. Rotation of the rod 6 in the reverse direction causes the member 15 to move rearwardly, whereby the toggle links 20 approach a parallel direction and draw the members 10 toward each other until the inner faces of the latter touch. It should be observed that when the members 10 are drawn together, the outer lower edges of same stand directly above the outer edges of the sole portion 3, so that the last can be readily inserted into or withdrawn from a shoe. Furthermore, the outer lower edges of the members 10 and, also, the outer rear edges of the same are preferably rounded to prevent same from cutting the shoe while the latter is being stretched. In operation, after the members 10 have been drawn together, as shown in Fig. 1, the last is inserted into the shoe (not shown in the drawings) in the usual manner, and then the rod 6 is turned in the proper direction to cause the member 15 to move forwardly, thereby causing the toggle links 20 to force the members 10 apart, with the result that the latter stretch the part of the shoe in engagement therewith. In order to remove the last from the shoe after the

latter has been stretched, the rod 6 is turned in the reverse direction to draw the members 10 together, after which the last may be withdrawn from the shoe.

It will be evident that, when the members 10 are moved apart to stretch a shoe as hereinabove described, the members 10 exert a uniform pressure upon the part of the shoe in engagement therewith, causing the latter to be stretched uniformly. In case it is desired to stretch the shoe greater at some particular part, as, for instance, at the part which would engage a corn or bunion on the wearer's foot, a block 30 having a convex outer surface may be attached to one of the members 10 by inserting the pin 31 borne by said block into an aperture 32 in said member, as depicted in Fig. 1, to effect such increased stretching of the shoe at the desired point. It will be observed that each member 10 is provided with a plurality of apertures 32 so that one block 30 or more may be attached thereto.

It should be understood that the last 1 and the members 10 may be made of wood or metal.

I claim:

1. A shoe-stretcher comprising a last having a recess in its upper forepart and a longitudinal opening in its upper rear part, a pair of separable members supported in the recess in said last, a screw-threaded rod extending through the opening in said last, the forward end of said rod extending between said members and having toggle-joint connections with same, means supported within the opening in said last for effecting longitudinal movement of said rod when the latter is rotated, and a pair of links pivotally connected to said last and having pivotal connections with said members.

2. A shoe-stretcher comprising a last having a recess in its upper forepart and a longitudinal opening in its upper rear part, a pair of separable members supported in the recess in said last, a screw-threaded rod extending through the opening in said last, the forward end of said rod extending between said members and having toggle-joint connections with same, means supported within the opening in said last for effecting longitudinal movement of said rod when the latter is rotated, and a pair of links pivotally connected to said last and having pivotal connections with said members, there being a slot in said last for the reception of said links.

3. A shoe-stretcher comprising a last having a recess in its upper forepart, a pair of separable members supported in the recess in said last and having registering depressions in their inner faces, a toggle-joint connecting said members and consisting of a U-shaped member, a pair of links having their inner ends pivoted to and between the

- flanges of said U-shaped member, a pair of channel-irons secured in the depressions in said separable members and having the outer ends of said links pivoted to and between their flanges, means carried by said last for actuating said U-shaped member, and means pivotally connecting said separable members with said last.
- 5 4. A shoe-stretcher comprising a last having a recess in its upper forepart and a slot extending rearwardly from the recess, a pair of separable members supported in the recess in said last, a pair of links having their forward ends pivotally connected to said members and their rear ends pivoted in the rear ends of the slot in said last, a toggle-joint connecting said members, and means carried by said last for actuating said toggle-joint.
- 10 5. A shoe stretcher comprising a last having a recess in its upper forepart and also having a pair of opposite longitudinal slots which communicate with said recess and which extend adjacent to the rear of the last, a pair of separable members slidably transversely throughout their lengths in said recess, links in said slots pivoted to the rear of the last and to the inner ends of said members, the inner sides of said members having sockets located between the ends and the top and bottom faces thereof, channel irons received in said sockets, a screw threaded rod carried by the rear of the last, a member connected to the rod to partake of the longitudinal movement thereof and having its ends receivable in the sockets, and toggle links pivoted to said member and to said channel irons.
- 15 6. A shoe stretcher comprising a last having a recess in its upper forepart and a slot extending rearwardly from the recess, a pair of separable members supported in the recess in said last, a pair of links having their forward ends pivotally connected to said members and their rear ends pivoted in the rear ends of the slot in said last, a toggle-joint connecting said members, and means carried by said last for actuating said toggle-joint.
- 20 7. A shoe stretcher comprising a last having a recess in its upper forepart and also having a pair of opposite longitudinal slots which communicate with said recess and which extend adjacent to the rear of the last, a pair of separable members slidably transversely throughout their lengths in said recess, links in the slots pivoted to the rear of the last and to the inner ends of said members, the inner sides of said members having sockets located between the ends and the top and bottom faces thereof, channel irons received in said sockets, a screw threaded rod carried by the rear of the last, a member connected to the rod to partake of the longitudinal movement thereof and having its ends receivable in the sockets, and toggle links pivoted to said member and to said channel irons.
- 25 8. In a shoe stretcher having a forepart and a rear part, the combination of a pair of separable members located at the forepart of the stretcher and being movable transversely throughout their length, means pivotally connected to said members for guiding the transverse movements thereof, toggle links pivoted to said members, and means supported by the rear part of the stretcher for actuating the toggle links to move said members toward and away from each other.
- 30 9. In testimony whereof I hereunto affix my signature in the presence of two witnesses.
